UNITED STATES PATENT OFFICE

95,841

DESIGN FOR AN ENSEMBLE DRESS

Jack Kirschner, New York, N. Y.

Application April 15, 1935, Serial No. 56,374

Term of patent 3½ years

To all whom it may concern:

Be it known that I, Jack Kirschner, a citizen of the United States of America, residing in Manhattan, county of New York, and State of New York, have invented a new, original, and ornamental Design for an Ensemble Dress, of which the following is a specification, reference being had to the accompanying drawing, forming part thereof, wherein,

The cross hatched lines at the front and back of the collar on the cape represent shirring.

I claim:

The ornamental design for an ensemble dress, substantially as shown and described.

JACK KIRSCHNER.
